(57) CLAIM

The ornamental design for an inverted-model-formula-one-race-cars-outfitted ceiling fan, as shown.

DESCRIPTION

FIG. 1 of the drawings is a perspective view of a ceiling fan embodying the design of my invention as viewed looking up from a position underneath the ceiling fan;

FIG. 2 is a top plan view of the upwardly facing side of the ceiling fan;

FIG. 3 is an elevation view of the front side;

FIG. 4 is an elevation view of the left side;

FIG. 5 is an elevation view of the right side;

FIG. 6 is an elevation view of the back side; and,

FIG. 7 is a bottom plan view of the downwardly facing side.
